BURRING MACHINE

Roger G. Cudini, Birmingham, Mich.

Application March 22, 1944, Serial No. 527,611

5 Claims. (Cl. 29—33)

The present invention relates to a burring machine and particularly relates to a machine of that type which is intended for use in removing burrs from elongated metal articles, such as strips of continuous hinge parts.

The primary object of the present invention is to provide improvements in machines of the type mentioned whereby the burrs formed in the manufacture of elongated hinge parts may be quickly and accurately removed.

Other objects of the invention will become apparent from the following specification, the drawings relating thereto, and from the claims herein-after set forth.

In the drawings, in which like numerals refer to like parts in the different views throughout,

Figure 1 is a partial, perspective view of a portion of the machine of the present invention, with the direction of the passage of the article through the machine indicated by the arrows;

Fig. 2 is a side elevational view of the apparatus shown in Fig. 1, taken from the right side thereof;

Fig. 3 is an enlarged, cross-sectional view taken substantially along the line 3—3 of Fig. 2;

Fig. 4 is a plan and cross-sectional view taken substantially along the line 4—4 of Fig. 3;

Fig. 5 is a side elevational view of the apparatus shown in Fig. 1 taken from the left side thereof;

Fig. 6 is an enlarged, cross-sectional view taken substantially along the line 6—6 of Fig. 5;

Fig. 7 is a perspective view of a portion of the hinge part and illustrating the burrs thereon;

Fig. 8 is a view similar to Fig. 7 and illustrating the finished hinge part.

The apparatus of the present invention is particularly designed to remove burrs which are formed on the elongated hinge parts during the manufacture thereof by the methods disclosed in the United States patent to Moynahan, et al. No. 2,288,013, granted June 30, 1942. Such hinge parts are formed of elongated metal elements having a main body portion 10 and a bead 12 along one edge thereof. In the formation of the bead, a perforation or aperture is provided therethrough. Segments of the perforated bead are cut away to leave perforated projections which may be interfitted with those of a cooperating strip. It is during the cutting away of these segments that the burrs 16 are left on the strip.

The machine of the present invention comprises a supporting standard generally in the form of a table frame, generally indicated at 19 and having a longitudinally extending bottom support member 20 upon which the bottom edge

5 of the hinge element rests. Longitudinally extending guide members 22 are mounted on the support 19 and are spaced from each other so that with the bottom members they form a guide channel within which the lower edge of the major portion 10 of the strip is received and engaged as it moves through the machine. The strip is so positioned that the bead is disposed upwardly and as the strip is moved through the machine, it is first engaged by a cutter 24 which engages the one side of the strip to remove the burrs along the bottom edges of the segments. The strip is then engaged by an abrasive stone 26 which has a contour complementary to that of the top of the bead to remove the burr along the top portion. As the strip moves further along the machine, it is engaged by another abrasive stone 28 which has a shape to engage a portion of the top and a portion of the side of the bead and along the edge of the segment to remove those portions of the burrs.

10 The strips are passed through the machine in the direction indicated by the arrows in Figs. 1, 2, and 5 and are moved through by hand tools indicated by broken lines 30 and 32 in Fig. 2. The leading edge of the strip may be positioned in the guide groove and one of the notches is engaged by the hand tool 30 as shown in Fig. 2 and such strip may then be pushed into and partially through the machine. As such leading edge passes beyond the other side of the machine, a notch on the workpiece may be engaged by hand tool 32 and pulled through the machine.

15 As mentioned above, the work strip is first engaged by the cutter 24 which is mounted in a holder 34 by means of a set screw 36. The holder 34 may be suitably mounted on the support in such a position that the cutter 24 is slidably mounted in a recess therein and may be so positioned that the cutting edge 38 of the cutter engages the adjacent side of the work strip. The work strip is resiliently urged against the cutter by means of a block 40 which is mounted on the end of a push rod 42 so that the face of the block 40 engages the opposite side of the work strip as shown in Fig. 3. Such rod 42 may be slidably received through a horizontal aperture 44 provided in a holder 46 which may be also mounted on the support. The block 40 is resiliently urged against the workpiece by means of a coil spring 48 which embraces rod 42 and has one end bearing against the block 40 and the opposite end bearing against a portion of the holder 46. The outer end of the rod 42 has a handle 50 formed thereon so that the block 40 may be withdrawn

to permit starting of a work strip through the machine. As the strip passes through the machine, the block 40 resiliently bears thereagainst to urge the opposite side into engagement with the cutting edge 38 of the cutter.

After portions of the workpiece have passed the cutter, they are engaged along the top surface by the abrasive stone 26. This stone 26 is mounted within a recess formed in a mounting housing 52 and may be removably fixed therein so that blocks of other contours may be inserted or the stone may be removed for the insertion of a new one after the first one is worn out. The housing 50 is pivotally connected to a pivot link 52 by means of a pivot pin 54. The opposite end of the link 52 is pivotally connected to an upstanding bracket 56 by means of a pivot pin 58. The bracket 56 is fixed to a mounting member 60, which in turn is adjustably mounted to upstanding frame members 62 and 64 which form parts of the main supporting structure 19. The member 60 is formed with vertical slots 66 adjacent the ends thereof which receive clamping screw 68 therethrough. The clamping screws 68 are threaded into frame members 62 and 64 so that by positioning the member 60 and tightening clamps 68, the member 60 may be vertically adjusted. The abrasive stone 26 is correspondingly adjusted.

In order to provide for a resilient engagement of the stone 26 with the top surface of the workpiece, a U-shaped strap 70 is fixed to the housing 50 so that the link 52 passes therethrough. A coil spring 72 is positioned within the member 70 so that one end thereof resiliently supports the link 52 and the other end thereof bears against the top surface of housing 50. A set screw 74 is passed through the bight of the U so that it engages the upper edge of the link 52 to adjust the effective pressure of spring 72.

Another U-shaped strap 76 is fixed to member 60 with the link 52 passing therethrough. A coil spring 78 is positioned within member 76 so that the lower end thereof resiliently bears against the top surface of link 52 and the opposite end thereof abuts against an adjustable plate 80. The plate 80 is fixed to the lower end of an adjusting screw 82 which is passed through the bight of member 76. A nut 84 is provided so that the tension on spring 78 may be adjusted. The spring 78 thus resiliently urges the stone 26 against the top surface of the workpiece, against the action of spring 72. In some instances, the spring 78 may be dispensed with and the weight of the stone and its mounting means will cause it to move downwardly against the action of spring 72 and resiliently against the top surface of the workpiece. As the work strip passes under stone 26, it is engaged as shown in Fig. 3. The mounting for plate 60 and the adjustment of the springs will permit adjustment of the stone with respect to the work. Furthermore, the mounting for the stone 26 on the pivot arm will permit its readily adjusting itself to the contour of the work strip as it passes therethrough.

After passing by stone 26, the work strip is engaged along the side having the burrs thereon or the same side as cutter 24 by the stone 28, as best shown in Fig. 6. The workpiece is held against the stone 28 by means of a backing plate 90 which is mounted on the main supporting frame and which has an integral depending portion formed with vertically extending slots 92. Clamping screws 94 are received through the vertical slots and are threaded into the supporting

member 20 which is fixed to the main supporting frame. Thus, the backing member 90 may be vertically adjusted so as to accommodate it to different size workpieces.

5 The stone 28 is mounted so that it may be adjusted toward and from the workpiece, so that it is resiliently urged about a pivot pin toward the workpiece and so that it may be vertically adjusted for different size workpieces.

10 The stone 28 is removably mounted within a recess 100 of a housing 102. Such stone may be fixed therein by means of a set screw or the like and may be readily removed for the insertion of another stone. The housing 102 is fixed to a plate 104 which passes under an upwardly offset member 106 which is fixed, by welding or the like, to one end of an elongated pivot arm 108 (Fig. 5). The plate 104 is pivotally connected to the upwardly offset member 106 by means of a pivot bolt 110. The member 106 has a pair of upstanding ears 112 formed thereon, each of which threadably receives therethrough a set screw 114. The inner ends of the set screws 114 abut against the back surface of housing 102. By adjusting the set screws 114, the housing 102, together with stone 28, may be adjustably pivoted about pivot 110 so that the stone 28 may be adjusted with respect to the work.

30 The arm 108 is pivotally connected to a supporting plate 116 by means of a pivot 117. The inner end of member 116 is disposed under plate 104 and is fixed to a mounting member 118. The mounting member 118 includes upstanding plate members and upper and lower horizontal members so that it is generally in the form of a box 35 I-section. Such horizontal plates are indicated at 120.

40 The arm 108, together with the upwardly offset portion 106, is resiliently urged toward the work by means of a coil spring 122. One end of the coil spring 122 is received over a projection 124 formed on the rear edge of offset portion 106; and the opposite end is received over a projection 126 formed on the inner end of an adjusting rod 128. The rod 128 is received through a mounting bracket 130, mounted on the top surface of horizontal member 120. A set screw 132 is threaded through member 130 and engages rod 128 so that the rod 128 may be adjusted to vary the spring tension of spring 122. It will thus be seen that since member 130 is fixed to the mounting member 118 that the arm 108 is resiliently urged toward the work about pivot 117. Housing 102, which holds stone 28, is fixed to the offset portion 106 so that the stone 28 is resiliently urged against the work to remove burrs therefrom as the work is passed thereby.

45 The member 118, including horizontal members 120, is mounted to a U-shaped strap 134. The member 118 is slidably disposed thereon so that the vertical members bearing against the inner sides of the strap and the flanges of the top horizontal members 120 slidably engage the upper edges of strap 134. Member 104 slidably rests 50 on top of upper member 120. Member 118 may be adjusted toward and away from the work by means of a rod 136 which extends through a tubular member 138 mounted on the outer end of strap 134. A set screw 140 is threadably mounted 55 on tube 138 and is adapted to engage the rod 136 to hold it in its adjusted position. By loosening the set screw 140, the rod 136 may be pulled in and out to slide the member 118, which serves as the support for the stone mounting mechanism, so that such mechanism may be adjusted 60

toward and from the work to accommodate the stone to different size workpieces.

The strip 134 has a depending portion 142 which is pivotally connected to a vertical slide 144 by means of a pivot 146. The entire mounting mechanism for stone 28, including strap 134 and mounting member 118, may thus be pivoted about shaft 146 to move the stone away from the work. The slide 144 is formed with a slot 148 through which a clamping screw 150 is received. The clamping screw 150 is threadably mounted to a depending bracket 152 which is fixedly connected to the main support. The bracket 152 has a horizontal bottom flange 154 through which an adjusting screw 156 is threaded. The upper end of adjusting screw 156 abuts against the bottom of slide 144. Thus, by loosening clamp 150 and turning screw 156, the slide 144, together with all of the mounting mechanisms for stone 28 may be vertically adjusted. The slide 144 may then be clamped in its adjusted position by tightening clamp 150.

In the operation of the machine above described, the work strip is inserted in the guideways and is then pushed and pulled through by the hand tools 30 and 32. The workpiece passes the cutter 24 which removes certain of the burred portions and thereafter passes by stones 26 and 28 in engagement therewith to remove the remaining burred portions. An air jet may be directed against the work adjacent the cutter 24 through an air tube 160 so as to clear the work, at this region, of the metal removed by the cutter.

Formal changes may be made in the embodiment of the invention without departing from the spirit and substance of the invention, the scope of which is commensurate with the appended claims.

What is claimed is:

1. A machine for removing the burrs on an elongated metal article comprising a support, guide means on said support for supporting and guiding said article as it moves along said support, a cutter mounted on said support and positioned to engage one side of said article, an abrasive member mounted on said support and positioned to engage the top surface of said article, another abrasive member mounted on said support and positioned to engage said one side of said article, and means holding said article in engagement with said cutter and said abrading members.

2. A machine for removing the burrs on an elongated metal article comprising a support, guide means on said support for supporting and guiding said article as it moves along said support, a cutter mounted on said support and positioned to engage one side of said article, means resiliently urging said article into engagement with said cutter, an abrasive member mounted on said support and positioned to engage the top surface of said article, another abrasive member mounted on said support and positioned to engage said one side of said article, and means resiliently urging said abrasive members into engagement with said article.

3. A machine for removing the burrs on an elongated metal article comprising a support, guide means on said support for supporting and guiding said article as it moves along said support, a cutter mounted on said support and positioned to engage one side of said article, means resiliently urging said article into engagement with said cutter, an abrasive member disposed above said support and positioned to engage the top surface of said article, means pivotally mounting said member for movement toward and away from said article, means resiliently urging said member into engagement with said article, another abrasive member on said support and positioned to engage said one side of said article, means pivotally mounting said member for movement toward and away from said article and means resiliently urging said another member into engagement with said article.

4. A machine for removing the burrs on an elongated metal article comprising a support, guide means on said support for supporting and guiding said article as it moves along said support, a cutter mounted on said support and positioned to engage one side of said article, means resiliently urging said article into engagement with said cutter, an abrasive member disposed above said support and positioned to engage the top surface of said article, means pivotally mounting said member for movement toward and away from said article, means resiliently urging said member into engagement with said article, means adjustably positioning said mounting means with respect to said article, another abrasive member on said support and positioned to engage said one side of said article, means pivotally mounting said member for movement toward and away from said article and means resiliently urging said another member into engagement with said article, and means adjustably positioning said last named mounting means with respect to said article.

5. A machine for removing the burrs on an elongated metal article comprising a support, guide means on said support for supporting and guiding said article as it moves along said support, a cutter mounted on said support and positioned to engage one side of said article, means resiliently urging said article into engagement with said cutter, an abrasive member disposed above said support and positioned to engage the top surface of said article and having a contour complementary to that of the adjacent surface of said article, means pivotally mounting said member for movement toward and away from said article, means resiliently urging said member into engagement with said article, another abrasive member on said support and positioned to engage said one side of said article and having a contour complementary to that of the adjacent surface of said article, means pivotally mounting said member for movement toward and away from said article and means resiliently urging said another member into engagement with said article.

ROGER G. CUDINI.
